HOUSING FOR A POWER GAS BURNER

William H. Moore, 218 Dorchester Ave., Syracuse, N.Y.

Continuation of design applications Ser. No. 59,451, Feb. 19, 1960, and Ser. No. 62,031, Sept. 6, 1960. This application Jan. 12, 1961, Ser. No. 63,766

Term of patent 14 years

(Cl. D81—2)

Figure 1 is a front perspective view of a housing for a power gas burner embodying my new design and shown on a reduced scale compared to Figures 2 to 5 inclusive;

Figure 2 is a front elevation thereof;

Figure 3 is a side elevation of the housing, the opposite side being a mirror image of this disclosed side;

Figure 4 is a top plan view of the housing;

Figure 5 is a rear elevation thereof;

Figure 6 is a front perspective view of a modified form of the housing as disclosed in Figure 1.

The front, top, side and rear views of Figure 6 are similar to Figures 2 to 5 inclusive, except that the top portion thereof is as shown in Figure 6.

This application is a continuation of my application Serial No. 59,451, filed February 19, 1960, and Serial No. 62,031, filed September 6, 1960.

I claim:

The ornamental design for a housing for a power gas burner, substantially as shown and described.
